(57) CLAIM

The ornamental design for a detachable lid for beverage container, as shown and described.

DESCRIPTION

FIG. 1 is a top plan view of a detachable lid for beverage container showing my new design;

FIG. 2 is a bottom plan view thereof;

FIG. 3 is a side elevational view thereof; and,

FIG. 4 is a perspective view thereof.

The broken lines shown on FIG. 4 are for illustrative purposes only and are hereby disclaimed as forming no part of Applicant's claimed invention.
